(57) **CLAIM**

The ornamental design for a lamp with speaker, as shown and described.

DESCRIPTION

FIG. 1 is a front bottom perspective view of a lamp with speaker showing our new design wherein the bottom of the lamp includes a plurality of light sources and at least a speaker surrounded by the plurality of light sources;

FIG. 2 is a front perspective view of the lamp with speaker;
FIG. 3 is a rear perspective view of the lamp with speaker;
FIG. 4 is a left side perspective view of the lamp with speaker;
FIG. 5 is a right side perspective view of the lamp with speaker;

FIG. 6 is a top perspective view of the lamp with speaker; and,
FIG. 7 is a bottom perspective view of the lamp with speaker.
